UNITED STATES PATENT OFFICE.

GEORGE S. MACLEOD, OF SEATTLE, WASHINGTON.

ANTIBALDNESS CAP.

Application filed October 10, 1923. Serial No. 667,626.

To all whom it may concern:

Be it known that I, GEORGE S. MACLEOD, a citizen of the United States, residing at Seattle, in the county of King and State of

5 Washington, have invented certain new and useful Improvements in Antibaldness Caps, of which the following is a specification.

This invention relates to caps or hats worn by men and boys and, more especially, 10 to a type of head covering shown and described in United States Letters Patent No. 1,434,745 issued to me November 7, 1922.

In the devices illustrated in said patent there are employed sweat band pads arranged 15 to prevent the hat or cap bearing against the wearer's head in a manner to compress or hinder the flow of blood through the arteries or veins which supply nourishment to the hair upon his scalp.

20 The object of the present invention is to provide a head covering which will perform the functions attained by said patented devices and be of more simple and inexpensive construction.

25 More specific objects and advantages of the invention will appear in the following specification.

The invention consists in the novel construction, adaptation and combination of 30 parts hereinafter described and claimed.

In the accompanying drawing,—

Figure 1 is a longitudinal vertical section on line 1—1 of Fig. 2 of a cap embodying my invention. Fig. 2 is a horizontal section 35 taken substantially through 2—2 of Fig. 1, parts being omitted. Fig. 3 is a perspective view illustrating the cap as worn. Fig. 4 is a front elevation of a person's head showing, diagrammatically, the principal blood 40 channels, arteries and veins, leading to and from the scalp to illustrate the use of the invention.

Referring first to Fig. 4, the reference numerals 5—5 designate arteries located at the 45 sides of the head and in front of the respective ears for conveying blood to the arterial branches, conventionally known as arterioles and capillaries, for supplying oxygen and other food matter to the roots of the hair in the scalp. The numeral 6 represents 50 tributary veins extending from the scalp and converging at about an inch above the hat line in a main vein channel 7 which extends downwardly through about the mid- 55 width of the forehead.

As practically 95 per cent of the blood

supplied to the scalp passes through the veins and arteries above named, other arteries and veins leading to and from the scalp need not be considered. 60

On the forehead and directly above the eyebrows and located in the hat line are regions indicated by 8, hereinafter designated as neutral areas, in which there are found practically no blood channels communicating with the scalp. 65

In carrying out the present invention I provide a cap or hat which is adapted to bear against the head at the neutral areas 8 and also at the back and sides of the head 70 to the rear of the arteries 5, but not against the areas occupied by the arteries and veins above mentioned.

Referring to the drawing and particularly to Figs. 1 and 2, a cap embodying the present invention consists of a crown 10, having a hem 11, a visor 12 and a sweat band 13 at the front. 75

The visor 12 is formed of a stiff material or, as shown in Fig. 1, of a central piece 14 of stiff material with top and bottom covering of fabric or other material which may be similar to that of the crown. The rear edge of the visor is formed with curved end portions to conform substantially with the curvature of the opposing portions of the wearer's head centrally of its width said visor being formed with a reentrant angle to afford a recess 15 of a substantially V-shape as shown in Fig. 2. 80

The material of the crown 10 is cut away or formed to provide at each side a recess 16 which extends approximately from positions above the wearer's ears to the adjacent ends of the visor. The crown is sewed or otherwise secured to the visor to follow the contour of the rear edge of the latter including that of the recess 15. 85

In the cap illustrated, is a strap 17 secured to the outside thereof by sewing as at 18 100 and 19 to the cap crown to the rear of and above the recesses 16. Said strap extends across the respective recesses 16 and in front of the latter the free ends of the strap are connected with each other as by means of 105 a buckle which is indicated by 20 in Fig. 2. Loops 21 secured to the opposite sides of the crown and in front of the respective recesses 16 may advantageously be employed to retain the strap in suitable position above the 110 visor.

The adjustment of the strap afforded by

its buckle connection enables the cap to be regulated to suitably engage the head.

The peculiar shape of the rear portion of the visor provides a space 22 exteriorly of the crown in front of the forehead, indicated by dotted lines 23 in Figs. 1 and 2, and affords places, as at 24 Fig. 2, to bear against the neutral areas 8 of the head, whence it is apparent that the vein 7 will not be compressed when the cap is worn.

In like manner, the recesses 16 of the cap afford channels in opposed relations with respect to the arteries 5 at the sides of the head to permit the free passage of blood through said arteries.

While I have illustrated and described the invention as embodied in a cap, I do not wish to be understood as confining myself thereto as the same principle may be used 20 with respect to a hat by substituting for the visor a brim, denoted by dotted lines 25 in Fig. 2, with a V-shaped notch in the front portion thereof.

What I claim, is,—

25 1. A head covering having a stiff visor formed in its rear portion with a centrally disposed relatively narrow recess of a substantially V-shape, a crown secured at its bottom directly to the rear edge of said visor 30 to retain the central front portion of the crown in spaced relation to the wearer's forehead to provide interiorly of the crown an air passage, said crown being cut away to provide therein a recess at each side of the cap and 35 adjacent to the respective ends of the visor, a loop secured to the crown in

proximity with each end of the visor, a strap sewed at the rear of the last named recesses to the crown, thence extending across said recesses of the crown and through said loops, and means for adjustably connecting together the ends of the strap above the visor.

2. In a head covering, a crown, a stiff visor secured throughout its rear edge directly to said crown, said edge being formed centrally of its width with a reentrant angular recess between two concave portions whereby said crown is retained within said recess in spaced relation with the head of the wearer, said concave portions affording bearing surfaces to the crown with respect to the head at opposite sides of said recess.

3. A head covering having a stiff visor formed in its rear portion with a centrally disposed relatively narrow recess of a substantially V-shape, a crown secured at its bottom directly to the rear edge of said visor to retain the central portion of the crown in spaced relation to the wearer's forehead to provide interiorly of the crown an air passage, said crown being cut away to provide therein a recess at each side of the cap and adjacent to the respective ends of the visor, and a strap sewed at the rear of each of the last named recesses to the crown, thence extending across said recesses of the crown to in front of the latter.

Signed at Seattle, Washington, this 3rd day of October, 1923.

GEORGE S. MACLEOD.
